CLAIM

We claim the ornamental design for an electric oven range, as shown and described.

DESCRIPTION

FIG. 1 is a front perspective view of an electric oven range showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is another front view of the electric oven range shown in an environment of use with a touch screen on the right side; and,

FIG. 10 is a front view of the electric oven range shown in another environment of use.

The broken lines shown in the drawings illustrate portions of the electric oven range that form no part of the claimed design. The dot-dot-dash broken line showing the border and the remaining broken lines except for the subject article in FIG. 10 illustrate environment and form no part of the claimed design.
